(57) **CLAIM**

The ornamental design for a circular ear rectangular body absorbing block, as shown and described.

DESCRIPTION

FIG. 1 is a perspective view of a circular ear rectangular body absorbing block showing my new design;

FIG. 2 is another perspective view showing my new design;

FIG. 3 is a left side view thereof;

FIG. 4 is a front view thereof;

FIG. 5 is a right side thereof;

FIG. 6 is a back view thereof;

FIG. 7 is a top view thereof; and

FIG. 8 is a bottom view thereof; and

FIG. 9 is an environmental view showing the absorbing block mounted into the body of a handgun; and,

FIG. 10 is another environmental view showing positioning of the absorbing block after initial assembly or during cleaning of the handgun.

The broken lines showing the handgun are for the purpose of illustrating environmental structure and form no part of the claimed design.
